UNITED STATES PATENT OFFICE.

THOMAS E. KNAUSS, OF NELSONVILLE, OHIO.

CAR-WHEEL.

SPECIFICATION forming part of Letters Patent No. 256,841, dated April 25, 1882.

Application filed March 7, 1882. (No model.)

To all whom it may concern:

Be it known that I, THOMAS E. KNAUSS, of Nelsonville, in the county of Athens and State of Ohio, have invented certain new and useful Improvements in Car-Wheel Hubs; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 represents an end view of the nave or hub of the wheel, looking from the outside. Fig. 2 represents a section taken on the broken line *x*. Figs. 3 and 4 represent detail views, showing the securing-plate.

This invention relates to improvements in car-wheels of that class which revolve on their axles, more particularly to the construction of their hubs for forming an oil-receptacle and means of securing the wheel on the axle.

The invention consists in a hub having partitions of peculiar construction and supply-holes, and also in a lock-plate, all as hereinafter set forth and explained.

In the annexed drawings, the letter *a* indicates the nave or hub of a wheel, having the bore or bearing *b* for the axle and the recess *c* for the axle-collar. Running across this hub lengthwise of the bore or bearing *b* are several partitions, *d*, which divide the interior of the hub into as many chambers. The partitions *d* extend from the bearing *b* radially 35 and up to the shell *a'* of the hub. They may be cast in one piece with the bearing and the shell or be separate and secured thereto. In either instance they extend from one to the other, as shown, bracing the whole structure.

These partitions may be made of two dimensions or thicknesses, the outer one, *e*, bracing the hub of the wheel, and the inner one, *f*, which is thinner, serving to divide the hub, as described. The difference in the thickness 40 of these partitions is shown in Fig. 2 and the thinner portions by dotted lines in Fig. 1; but these partitions may be made of the same thickness throughout, this not being material.

In these partitions are cut passages *g*, of any 45 suitable size and shape. These passages permit a complete flow around the hub, as hereinafter described. In each of the chambers of the hub, between the partitions, apertures *h* are made in the box *i*, leading into the bore

b. These apertures have a flare above and 55 below, as shown, so that their passage-ways *l* are smaller than their tops and bottoms. This construction forms an excellent oil-chamber for the hub, for the partitions force the lubricant against the hub and the passages *g* 60 allow of a steady flow around it, thus inducing action at the apertures *h*, and these by their peculiar shape conduct the lubricant to the bore and then spread it on the journal.

At the outer end of one or more of the partitions *d* the hub *a* is provided with an offset or flange, *k*, extending on both sides of the partitions, and having the bevel *m* and straight face *n*.

The locking or axle-securing plate *p* is provided with a bevel, *q*, to fit the under bevel, *m*, of offset *l*, and bears against the face *n*. This plate has two lugs, *r*, one of which comes on each side of partition *d*, holding the plate firmly in position, while the inner notched end, *s*, fits 75 in groove *t* at the end of the axle and holds the wheel on. In Fig. 1 this plate is shown in position by dotted lines. The plate is prevented from coming off by the cover-cap *v*, which is bolted to the hub, and has an oil-hole, 80 *w*. If desired, more than one of these plates can be employed.

This provides a simple and easy way of securing the wheel to the axle, keeping it firmly in place, and yet it can be quickly and readily 85 released.

Having described my invention, what I claim is—

1. A car-wheel hub having partitions which extend lengthwise of the bearing and from 90 the latter to the shell, and are provided with passages for the lubricant, and also having apertures between such partitions, all as set forth.

2. In a car-wheel hub provided with a lubricating-chamber, the apertures *h*, having their passage-way *l* smaller than their tops and bottoms, as set forth.

3. The hub having the offset and partitions, in combination with the plate having the lugs 100 and the notch, and the axle having the groove, all as set forth.

In testimony that I claim the foregoing as my own I affix my signature in presence of two witnesses.

Witnesses: THOS. E. KNAUSS.

J. R. HICKMAN,
FRANK PATTON.
